CONDENSATE COLLECTOR FOR TOILET FLUSH TANKS

Harry W. Addison, Jr., Marshall, Minn.

Application November 9, 1953, Serial No. 390,998

4 Claims. (Cl. 4—252)

This invention relates to a simplified and substantially entirely concealed condensate collector for toilet flush tanks and the like.

Many different types of devices have been invented in an attempt to solve the problem of preventing the condensed moisture on the outside of a toilet flush tank from dripping onto the floor of the bathroom. Most of these devices are conspicuous and require a relatively expensive collection tray into which the condensate drips and from which the collected liquid must be drained.

It is an object of my invention to provide an extremely simple, yet highly efficient, condensate collector for toilet flush tanks and the like which will absorb the condensate moisture received from the flush tank surface and drain the same into the toilet bowl through absorbent moisture-conducting elements while maintaining the entire assembly in substantially entirely concealed position directly below the flush tank bottom.

More specifically, it is an object to provide an absorbent type drip collector having an absorbent member underlying at least the outer peripheral portion of a toilet flush tank to collect the condensate dripping therefrom, said absorbent member having an absorbent drainage web connected therewith and adapted to extend downwardly therefrom when in operative position to carry off excess moisture and drain the same directly into the toilet bowl.

It is still another object to provide an absorbent drip collector for toilet flush tanks and the like which includes a double surfaced absorbent member with the upper surface underlying at least the outer peripheral portion of a toilet flush tank and the under surface connected with the upper surface to provide an exposed evaporation bottom surface from which a relatively large volume of moisture will be evaporated, and said drip collector including an elongated flexible absorbent moisture-conducting element through which excess accumulated moisture may be carried from the absorbent collector member into the toilet bowl.

These and other objects and advantages will more fully appear from the following description made in connection with the accompanying drawings, wherein like reference characters refer to the same or similar parts throughout the several views, and in which:

Fig. 1 is a pre-assembly view showing all of the disassembled parts in top plan;

Fig. 2 is an end elevational view partially in transverse vertical section showing my device in assembled operative position mounted on a toilet with the seat and cover removed;

Fig. 3 is a rear elevational view thereof;

Fig. 4 is a fragmentary vertical sectional view taken substantially along the line 4—4 of Fig. 1;

Fig. 5 is a fragmentary side elevation of the structure shown in Fig. 3 with portions thereof shown in vertical section;

Fig. 6 is a perspective view showing my device mounted on an alternative type of toilet with the cover and seat removed;

2

Fig. 7 is a fragmentary rear elevational view partially in section of the structure shown in Fig. 6; and

Fig. 8 is a fragmentary transverse sectional view taken substantially along the line 8—8 of Fig. 7 and showing the tank in side elevation.

As illustrated in Figs. 2 and 3, I show one type of a conventional flush tank construction. The toilet bowl in this form of construction is designated by the numeral 10, the flush tank by the numeral 11, the inter-connection 10 elbow conduit between the tank and the bowl by the numeral 12, and the water supply pipe by the numeral 13.

My new absorbent drip receiver for collecting the condensate dripping from the flush tank during warm weather consists in a flat, inconspicuous drip collecting structure which, in the form shown, is made in two sections, respectively designated by the letters A and B. Also, in the form illustrated, each of the sections A and B has a flat supporting plate, respectively designated by the numerals 14 and 15, and said plates have the inwardly and forwardly extending drainage web supporting arms, respectively designated by the numerals 16 and 17. These web supporting arms 16 and 17 each have a central depressed portion with a row of drainage apertures, respectively designated by the numerals 16a and 17a, formed therethrough. Absorbent pads, respectively designated by the numerals 18 and 19, are respectively mounted around the plates 14 and 15 as by being secured to the top and bottom surfaces thereof by any suitable means such as by being glued thereto by a suitable waterproof type of adhesive. These pads 18 and 19 are made from highly absorbent, flexible sheet material and, in the form illustrated, the lower layer thereof is continuous, as best shown in Fig. 7, and the marginal edge portions extend up and around the edges 35 of said plates and form the drip receiving and collecting portion of the device by being securely anchored to the marginal edge portions of the supporting plates 14 and 15, as best shown in Fig. 1. The outer marginal portions of the top absorbent cover flaps are positioned in 40 underlying relation to the peripheral edge portions of the flush tank 11, as best shown in Figs. 2 and 3, and receive and collect the condensate dripping from the lower edges of the sides of said tank. The plates 14 and 15 are, of course, constructed of any suitable flat, substantially rigid material which is not affected by the presence of moisture, such as aluminum or plastic sheet material.

In order to conceal the device as much as possible, the drainage web supporting arms 16 and 17 have a pair of drainage webs 20 and 21 mounted only on the bottom side thereof with their upper ends securely connected with the forward portion of the bottom layers of the flexible absorbent pads 18 and 19 as by forming continuations thereof. While I have found that heavy turkish toweling material works very satisfactorily for these pads 18 and 19, said pads could also be cut directly from stiff porous and absorbent material which would, of course, obviate the necessity of using the supporting plates 14 and 15. The drainage webs 20 and 21 are securely anchored to the bottom sides of the arms 16 and 17 and extend forwardly therefrom and downwardly a slight distance below the upper edge of the toilet bowl 10 at the rear thereof, as best shown in Fig. 2. The drainage webs 20 and 21 are cut off to maintain the same above the water level in the toilet bowl 10 at all times and may be protected to facilitate cleaning thereof by a metal or other protective element as best shown at 22 and 23 of Fig. 1, and the web portion disposed therebelow is cut off as shown in Fig. 2, and said two webs depend directly from the forward ends of the arms 16 and 17 across the rear top surface of the toilet bowl and hang downwardly at the rear of the bowl to deliver by gravity and capillary action of the absorbent material the

excess water collected in the bottom layer of the respective absorbent pads. It is obvious that the upper surfaces of the absorbent pads receive and collect the moisture from the outside of the tank 11 and said moisture is carried downwardly therefrom to the bottom surface of the pad which is substantially entirely exposed to the air and forms an evaporating surface from which a large portion of said moisture is evaporated. In the event that the rate of evaporation due to high humidity of the air is insufficient to prevent saturation of the lower absorbent layer, the excess water accumulating therein is removed therefrom by the drainage webs 20 and 21 which are, as has been previously stated, respectively connected with the lower layers of the drainage pads and the moisture passes by gravity and capillary action from said layers to the drainage webs 20 and 21 and, by the same gravity and capillary action, drips from said webs into the toilet bowl.

Suitable means are provided for positively securing the section A and B in underlying relation to the tank 11. In the form of connection between the flush tank and toilet bowl illustrated in Figs. 2 and 3, the elbow conduit 12 provides an accessible attachment to which a clamp 24 may be securely anchored. A clamping screw 25 may be used to securely attach said clamp 24 to the upper portion of the conduit 12. A horizontally disposed sleeve 26 is fixed to the rear portion of clamp 24 and a pair of retaining arms 27 and 28, having elongated straight shank portions at the inner ends thereof and pressure-applying fork elements 27a and 28a at the other ends thereof, are inserted through said sleeve, as best shown in Figs. 2, 3 and 5, and the arms 27 and 28 through forks 27a and 28a thus exert upwardly directed retaining pressure on the bottom of the two sections A and B respectively and hold said sections securely against the bottom surface of tank 11.

With the type of toilet bowl illustrated in Fig. 6 wherein the rear of the bowl extends rearwardly to underlie and support the flush tank thereon, it is obvious that the clamp 24 and sleeve 26 cannot be used. However, the toilet bowl 29 with tank 30 mounted thereon, as illustrated in Figs. 6, 7 and 8, is constructed to permit the sections A and B to be positioned between the rearwardly extended portion 29a of bowl 29 and the bottom of tank 30, and there is provided sufficient space between said flush tank bottom and the top of rearwardly extending portion 29a to permit the inner shank portions of retaining arms 27 and 28 to be positively wedged therebetween to force the supporting forks 27a and 28a respectively against the bottom surfaces of Sections A and B and positively hold the top surfaces of said sections in engagement with the bottom of the flush tank 30. As best shown in Fig. 1, Section A is recessed to receive the inlet conduit 13 and of course a recess of sufficient size must be provided in the central portion of the sections A and B to provide clearance for the elbow conduit 12.

It will be seen that I have provided a relatively simple and inconspicuous drip collector for the condensate produced on the outside of toilet flush tanks during warm humid weather, which collector by means of a highly absorbent pad will carry the collected moisture by capillary action from the upper surface thereof to the lower exposed surface from which a substantial portion of said moisture will be evaporated. It should also be noted that the provision of an highly absorbent discharge web 65 provides means for carrying off excess moisture which

cannot be evaporated from the lower surface of the absorbent pad and discharges said excess moisture by capillary action into the toilet bowl.

It will, of course, be understood that various changes may be made in the form, details, arrangement and proportions of the parts without departing from the scope of this invention which, generally stated, consists in the matter shown and described herein and set forth in the appended claims.

What I claim is:

1. A condensate collector and evaporator for toilet flush tanks comprising a pair of cooperating flat sections, each including a substantially rigid supporting plate with a sheet of flexible, highly absorbent material secured to the top and bottom surfaces thereof and overlying, at least the outer marginal portion of the top surface, each of said absorbent sheets having an elongated web of absorbent material connected with the bottom layer thereof, and an elongated arm structure fixed to each of said plates and extending inwardly therefrom along the front edge thereof and having a portion of the elongated web connected therewith, said webs respectively carrying off excess moisture accumulated in the bottom absorbent layer.

2. The structure set forth in claim 1, and said web supporting arms having the webs mounted only on the bottom surface thereof and having a plurality of spaced apertures in the top surface to permit the moisture dripping thereon to contact said web and be carried off thereby.

3. A condensate collector and evaporator for toilet flush tanks comprising a pair of cooperating flat sections having absorbent top and bottom surfaces at least around the marginal portions thereof and constructed of a size and shape to underlie at least the marginal edge portions of a toilet flush tank, an elongated hollow member constructed and arranged to be securely anchored to an intermediate portion of the flush tank, a pair of resilient elongated wedging arms having their inner end portions received within said hollow member to urge by cantilever action the outer ends upwardly into respective engagement with the undersides of said sections to hold said sections in engagement with the bottom of the flush tank, and drainage means for carrying off excess moisture accumulated on the bottom absorbed surface of each of said sections.

4. The structure set forth in claim 3 and the means for anchoring said hollow member comprising a clamping element constructed and arranged to be securely clamped to the conduit between the flush tank and the toilet bowl and fixed to said elongated hollow member to securely mount the same below the flush tank.
